UNITED STATES PATENT OFFICE.

JOHN J. LYONS, OF BROOKLINE, MASSACHUSETTS.

CORK-EXTRACTOR.

1,243,845.

Specification of Letters Patent.

Patented Oct. 23, 1917.

Application filed March 21, 1916. Serial No. 85,712.

To all whom it may concern:

Be it known that I, JOHN J. LYONS, a citizen of the United States, residing at Brookline, in the county of Norfolk and State of Massachusetts, have invented new and useful Improvements in Cork-Extractors, of which the following is a specification.

This invention relates to a tool for extracting corks from bottles, jugs and other like vessels. Oftentimes a cork becomes pushed into a bottle or jug and it is then a very difficult matter to remove the same from the bottle or jug.

It is the object of this invention to provide a cheap, convenient and easily manipulated tool whereby a cork may be removed from the interior of a bottle.

The invention consists in a device of the character set forth in the following specification and particularly pointed out in the claims.

Referring to the drawings:

Figure 1 is a front elevation of my improved cork extractor.

Fig. 2 is a side elevation of the same broken away to save space.

Fig. 3 is a sectional elevation of a bottle broken away to save space illustrating a cork in position to be removed by my improved cork extractor.

Fig. 4 is a sectional plan on line 4—4 of Fig. 3.

Fig. 5 is a sectional plan taken on line 5—5 of Fig. 3.

Fig. 6 is a side elevation of a modified form of cork extractor broken away to save space.

Fig. 7 is a front elevation of another modified form of cork extractor embodying my invention.

Fig. 8 is a side elevation viewed from the right of Fig. 7.

Fig. 9 is a sectional plan taken on line 9—9 of Fig. 8.

Like numerals refer to like parts throughout the several views of the drawings.

In the drawings, 10 is the shank portion of the cork extractor and 11 the handle, said shank portion 10 terminating in a laterally extending prong 12. The shank portion 10 is curved laterally adjacent to the prong 12 at 13 and is provided with a pair of laterally extending prongs 14.

In operating the device the bottle 15, if empty, is inverted before removing the cork 16 and the pronged end of the shank 10 is

inserted in the bottle through the neck portion 17. The cork 16 drops into the inner end of the neck 17 and as the extractor is drawn toward the outer end of said neck, 60 the prongs 12 and 14 engage said cork, as illustrated in Fig. 3. Then the operator pulling upon the cork extractor by means of the handle 11 draws the cork out of the bottle through the neck 17. The prong 12 65 engages one end of the cork during this operation, while the prongs 14 engage the side portion of the cork on opposite sides of the shank 10.

By employing three prongs the cork is 70 firmly held against tipping and becoming disengaged from the extractor. Also by using three prongs, with the prongs 14 located on opposite sides of the shank 10, the cork will be grasped at three points out of 75 alinement with each other longitudinally of the cork so that there is less liability of splitting the cork in withdrawing the same from the bottle. The curved cam-shaped portion 13 of the shank enables the user to 80 tip the extractor, when he is first causing the same to engage the cork, so that the prong 12 can first be manipulated to engage the end of the cork. As the cork is being withdrawn the cam-shaped portion 13 engages 85 the inside of the neck of the bottle and forces the prong 14 still farther into the cork to firmly anchor the cork to the extractor.

In Fig. 6 a modified form of my cork extractor is illustrated in which the prongs 18 and 19 are connected together by a straight portion 20 of the shank 21.

Referring to the modified form of my invention illustrated in Figs. 7, 8 and 9, 22 95 is the shank of the extractor and 23 is the handle fast thereto. A laterally extending prong 24 is provided at the end of the shank 22 and also two laterally extending prongs 25 are provided which are located on opposite sides of the median axial line of said shank.

The shank 22 is divided into two parts 26 and 27. The part 26 is cylindrical in cross section so that when the device is in 105 use and the handle is grasped by the user the cylindrical portion 26 of the shank may come between the fingers of the hand of the user without injuring the same. The portion 27 is flattened and has a substantially 110 flat inner face 28 and a convexly curved outer face 29 as clearly illustrated in Fig.

9. The portion 27 of the shank is curved longitudinally thereof to give the same a convexly curved outline longitudinally of said shank as at 30. By having a flat face 5 28 and a convexly curved face 29 the end of the shank which grasps the cork takes up a small amount of room in the interior of the neck of the bottle and approximately fits the inner surface of the neck of the 10 bottle and assists in preventing the cork from tipping out of position when the inner face 28 is pressed against the periphery of the cork during the withdrawal of the same from the bottle.
15. It will be noted that in each of the different forms of my invention hereinbefore set forth the pairs of laterally extending prongs 14, 19 and 25 have the edge thereof which is farthest removed from the end 20 prong of the extractor extending substantially at right angles to the shank. This angle may be a right angle or it may be an acute angle, it being desirable to have the angle such that when a cork is being withdrawn there is no tendency for the pair of prongs to be forced out of the cork, but, on the contrary the tendency is to have said prongs sink into and obtain a secure hold 25 against withdrawal from said cork.
30. The extractor illustrated in Figs. 7 to 9 inclusive is operated in substantially the same manner as hereinbefore described with relation to the form of my invention illustrated in Figs. 1 to 5 inclusive.
35. As hereinbefore set forth and as clearly illustrated in Fig. 8 the shank is convexly curved longitudinally thereof. This convex curvature may be greater or less to suit different sizes of corks, the objects of this 40 construction being to cause the pulling force

upon the cork to be applied as nearly as possible coinciding with the median axial line of the cork which is being removed.

Having thus described my invention, what I claim and desire by Letters Patent to secure is:

1. A tool for extracting a cork from a bottle comprising a shank portion and a single pointed centrally located prong projecting laterally from one end of said shank 50 and a pair of prongs located on opposite sides of said shank, each prong of said pair of prongs having the edge thereof which is farthest removed from said end prong extending substantially at right angles to said 55 shank, said end prong being separated from said pair of prongs by a portion of said shank having an inner edge substantially free from projections.

2. A tool for extracting a cork from a 60 bottle comprising a shank portion and a single pointed centrally located prong projecting laterally from one end of said shank and a pair of prongs located on opposite 65 sides of said shank, each prong of said pair of prongs having the edge thereof which is farthest removed from said end prong extending at an angle less than an obtuse angle to said shank, said end prong being separated from said pair of prongs by a portion of said shank having an inner edge 70 substantially free from projections.

In testimony whereof I have hereunto set my hand in presence of two subscribing witnesses.

JOHN J. LYONS.

Witnesses:

CHARLES S. GOODING,
